UNITED STATES PATENT OFFICE.

WILLIAM R. DUNCAN, OF CHICAGO, ILLINOIS.

STOP FOR PHONOGRAHS.

Application filed November 21, 1921. Serial No. 516,723.

To all whom it may concern:

Be it known that I, WILLIAM R. DUNCAN, a citizen of the United States, residing at Chicago, in the county of Cook and State of Illinois, have invented certain new and useful Improvements in Stops for Phonographs, of which the following is a specification.

This invention relates to an automatic stop which is particularly applicable to phonographs or talking machines of the Edison type in which a vertically vibrating stylus coacts with a flat disc or record.

The objects of this invention are to provide a particularly simple and efficient stopping mechanism which may be readily applied to machines which have been constructed or which may be incorporated in new machines; to provide an automatic stopping device which will be actuated by the movement of a floating weight when it reaches the end of the groove in the record; and in general to provide such an improved construction as will be described more fully in the following specification.

In the accompanying drawings illustrating this invention

Figure 1 is a side view partially in section showing an Edison phonograph and my improved stop applied thereto;

Figure 2 is an enlarged sectional plan view taken on the line 2-2 of Figure 1;

Figure 3 is a section taken on the line 3-3 of Figure 1;

Figure 4 is a side view of the attachment in position;

Figure 5 is a side view of the stop shown on an enlarged scale;

Figure 6 is a front view;

Figures 7 and 8 are cross sectional views; and

Figure 9 is a longitudinal sectional view.

The phonograph 10 is provided with a combined tone arm and amplifier 11 which is mounted in the well-known manner and carries the reproducer 12. In this particular form of phonograph or talking machine the reproducer is provided with a floating weight 13 which is carried at one end by a spring 14 which is pivoted to the inner end 15 of the reproducer, the arrangement being such that the outer end of the weight may swing up and down as well as laterally. The outer end of the weight is provided with a limit pin 16 which coacts with a limit loop 17. One of the characteristic features of the

operation of this instrument is that when the stylus 18 leaves the end of the groove and runs out on the plane surface of the record 19 the floating weight will always swing in one direction with respect to the reproducer, such movement being limited by the loop 17. It is this relatively slight movement of the weight which I take advantage of in order to stop the machine. The spring 14 has a projection or collar 20 which rotates with the swinging movement of the weight. I secure a finger 21 to this collar by means of a clasp 22 or any other suitable manner so that the finger will swing or vibrate with the weight. The stopping mechanism 23 is fixed to the end 15 of the reproducer so that it may be actuated by the inner finger 21. This mechanism has a base 24 with a bracket or fastening portion 25 which engages with the end 15 of the reproducer and is held by means of a set screw 26. A tube 27 extends upwardly from the base and has a plunger 28 mounted therein. The lower end of this plunger is provided with a foot 29 such as a ball of felt or the like for engagement with the record 19 for stopping the rotation of the same. A compression spring 30 is inserted between the upper end of the plunger and the cap 31 of the tube 27 and tends to press the plunger downwardly. The plunger is held in raised position by means of a pin 32 which passes through the plunger and extends out through slots 33 in the side of the tube and engages with a yoke 34. This yoke is pivoted at 35 to an arm 36 which is secured to the base 24. The yoke extends beyond the pivot and has a thumbpiece 37 which is arranged adjacent to a similar thumbpiece 38 on the arm 36 so that the yoke may be raised and the spring compressed by pressing these thumbpieces together. The free end of the yoke is held in raised position by a detent 39 which engages with a catch 40 on a trip lever 41 which is pivoted at 42 to the cap 31. The detent and catch are preferably made of small pieces of hardened steel or the like so that they will operate with little friction. The shape of the trip lever 41 is such that it will swing by gravity to locking position. The lower end of this lever passes through a hole 43 in the base 24 and engages with one end of a horizontal lever 44 which is pivoted at 45 to the base 24. The opposite end of the lever 44 is engaged by the pin or finger 21.

When the operator starts the phonograph for playing a record the operator presses the thumbpieces 37 and 38 so as to raise the plunger 28 away from the disc and the plunger is held in this position by the catch 40. When the stylus reaches the end of the groove and passes up on the surface of the record the floating weight 13 is swung laterally and causes the pin 21 to press against the lever 44 which in turn moves the trip lever 41 outwardly and releases the plunger 28 so that the felt ball or foot 29 will press down against the record and act as a brake to stop the machine. The arrangement of parts and details of construction may be varied for commercial purposes without departing from the scope of this invention and therefore I do not wish to be limited to the exact construction shown and described, except as specified in the following claims in which I claim:

1. The combination with a phonograph for disc records having a floating weight, of means for stopping the machine and mechanical means actuated by the floating weight for causing the stopping means to act.

2. The combination with an Edison talking machine, of a stopping device secured to the reproducer and means coacting with the floating weight for actuating the stopping device when the stylus passes from the end of the groove in the record.

3. The combination with a phonograph, of a spring plunger mounted on the reproducer and adapted to engage with the record for stopping the machine, means for holding the plunger in raised position and means actuated by the stylus support for releasing the plunger when the stylus passes from the groove onto the surface of the record.

4. The combination with a phonograph having a floating weight, of a bracket adapted to be secured to the reproducer, a spring plunger in said bracket, means for raising said plunger, a catch for holding the plunger in raised position, a finger connected to the floating weight and means operated by the finger for releasing the catch.

5. A stopping device for phonographs having floating weights, comprising a base adapted to be secured to the reproducer, a tube mounted on said base, a plunger in said tube, a ball of resilient material at the end

of the plunger for engagement with the record, a spring tending to press the plunger downwardly, a yoke pivoted at one side of the tube, a pin through said yoke engaging with the plunger, thumbpieces for swinging the yoke, a detent at one end of the yoke, a lever pivoted at the top of the tube and having a catch for engagement with the detent, a finger adapted to be secured to the floating weight to swing therewith in a lateral direction, said finger being adapted to actuate the trip lever for releasing the plunger.

6. The combination with an Edison phonograph, of a finger secured to the floating weight and adapted to swing laterally therewith, a bracket secured to the reproducer, a tube on said bracket, a plunger mounted in said bracket, a foot of resilient material at the lower end of the plunger for engagement with the record, a spring in the tube tending to press the plunger downwardly, a yoke pivoted at one side of the tube and connected with the plunger for raising the same, a detent on said yoke, a trip lever pivoted above the detent and having a catch for engagement therewith, and a horizontal lever pivoted to a bracket, one end of said lever being adapted to be engaged with the finger for swinging the same to cause the other end of the lever to engage with the trip lever for releasing the plunger.

7. A stop for phonographs comprising a brake adapted to engage with the record, a floating weight and mechanical means controlled by said weight for actuating the brake at a predetermined time.

8. In an apparatus of the character set forth, the combination with a rotatable record and a floating weight, of means for stopping the record, a support for said stopping means and a trip adapted to be actuated by the floating weight for causing the stopping means to act at a predetermined time.

9. The combination with a phonograph, of a vertically movable spring plunger, means for holding the plunger in raised position and means for releasing the plunger to permit it to engage with the record for stopping the machine when the record has been finished.

WILLIAM R. DUNCAN.
